UNITED STATES PATENT OFFICE

DAVID G. BERNARD, OF CHICAGO, ILLINOIS, ASSIGNOR, BY MESNE ASSIGNMENTS, TO
FRANKLIN W. KOHLER, OF CHICAGO, ILLINOIS

DEVICE FOR DELIVERING PAPER TO PRINTING PRESSES

Application filed April 23, 1928. Serial No. 272,163.

This invention relates to devices for delivering paper to printing presses and has for its object to provide a new and improved device of this description.

5 The invention has as a further object to provide a device for delivering paper to printing presses which gives a complete and full control of the paper on the roll while it is being delivered to the press.

10 The invention has as a further object to provide a device for delivering paper to printing presses which will prevent the paper from running off of the roll when the press is slackened or stopped.

15 The invention has further objects which are more particularly pointed out in the accompanying description.

Referring now to the drawings, Fig. 1 is an end view of one form of device embodying the invention.

20 Fig. 2 is a view similar to Fig. 1 showing the paper which is delivered to the press as running in the opposite direction to that shown in Fig. 1.

25 Fig. 3 is a rear elevation showing the construction illustrated in Figs. 1 and 2.

Fig. 4 is an enlarged sectional view showing the lower end of one of the belts and associated parts, as illustrated in Fig. 1.

30 Fig. 5 is a sectional view taken on line 5-5 of Fig. 4.

Fig. 6 is a side view showing a modified construction.

Fig. 7 is a sectional view taken on line 35 7-7 of Fig. 6.

Like numerals refer to like parts throughout the several figures.

Referring now to the drawings, I have illustrated a movable support for a plurality of rolls of paper with a series of endless belts arranged to engage one of the rolls.

For purposes of illustration the roll supporting device is shown as a shaft 1 having arms 2 and 3 thereon, the shaft 1 being rotatably mounted upon supports 4 and 5. Some means is provided for rotating the shaft 1 and the arm 3. As herein shown this is accomplished by means of a worm gear 6 connected with the shaft 1, said gear being actuated by a worm 7 operated by a motor 8.

Mounted between the arms 2 and 3 are the rolls of paper 9, 10, and 11. Associated with the roll support are a series of endless belts 12, 12a, 12b, and 12c. These belts pass over a series of direction changing devices 13, 14, 15, 16, 17, and 18. All of the direction changing devices are fixed in position except the direction changing device 15 which is movable so as to keep the belt taut and thus keep it in proper relation to the roll of paper at all times, as the roll gets smaller as the paper is unwound therefrom.

These direction changing devices are preferably pulleys or rotatable devices of any suitable construction mounted so as to rotate when the belt is in operation. The direction changing devices 14 are mounted on a shaft 14a which is driven from any suitable source of power.

Some means is provided for applying pressure to the direction changing device 15 to keep the belt taut and this means also moves the direction changing device 15 as the roll from which paper is being driven to the press decreases in diameter so as to keep the belts 70 at all times in proper position with relation to the roll of paper.

In the construction shown this is accomplished by connecting with each direction changing device 15 a weight 20. This weight 80 is adjustably mounted on an arm 21 and is held in any adjusted position by a set screw 22. Each arm is pivoted between its ends to a fixed part or rod 23. The end of the arm farthest from the weight is connected with the direction changing device 15. In the construction shown this arm is provided with branches 24 and to these branches is connected a shaft 25 upon which the direction changing device rotates.

It will be noted that the weight and the arm are similar for each of the belts and that they are independent of each other so that each belt will be kept in proper contact with the roll of paper regardless of irregularities of the surface thereof. I prefer to have the belts narrow and to use a number of such belts. In the construction shown four belts are used but it is, of course, evident that the number may be varied if desired.

I prefer to have the belts driven and they may be run at any desired speed but preferably at a speed approximately equal to or somewhat less than the speed of the paper running to the press. The belts are arranged so as to have a comparatively large area of contact with the roll of paper. This result is secured by having a direction changing device above and below the roll, such as 13 and 18 and locating these direction changing devices beyond the vertical line passing through the face of the roll where it engages the belt.

The direction changing devices 13 and 18 may, of course, be placed in any suitable position and I prefer to have them placed on a vertical line which passes on the opposite side of the center of the roll from that engaged by the belt so that there will be a very large area of contact between the belt and the roll. In Fig. 1 the web of paper 26 passing from the roll to the press is shown as passing downward in contact with the belt and over the direction changing devices 18 and 17 where it passes over the direction changing device 27 and separated from the belt passing downwardly to the press. Under these conditions I prefer to provide an additional direction changing device 28 for the belt which insures the separation of the belt from the paper as shown in Fig. 1.

When the paper passes around the direction changing devices around which the belt also passes, some means is provided for arranging the parts so that they will not interfere with the proper operation of the paper. Under such conditions the direction changing devices 17 and 18 are preferably continuous from end to end so as to act as rollers for the paper and at the points where the belts are located, the direction changing devices are recessed or provided with annular grooves 29 into which the belts are received, the grooves being of such depth that the belts will not project beyond the surface of the rollers, for otherwise they would cause bulging of the paper and interfere with the proper operation of the device, (see Figs. 4 and 5).

In Fig. 7 I have shown a modified construction where the belt at the lower end passes around only one direction changing device 30. The web 26 of the paper being delivered to the press passes around the direction changing devices or rollers 31 and 32 and then around the direction changing device 33 to the press. A spring 33a normally tends to keep the paper taut.

The rollers 31 and 32 may be driven from the direction changing device 30 by means of a link belt 34 which passes around a sprocket wheel 35 rotating with the direction changing device 30, said link belt also passing around the sprocket wheels 36 and 37 on the direction changing devices 31 and 32. This construction avoids the necessity of providing the direction changing device over which the paper

passes, with annular grooves for the belts. In Fig. 2 I have shown a construction wherein the web of paper 38 from the roll instead of running downwardly runs upwardly to the press around the direction changing devices 39 and 40. In this arrangement, the same number of direction changing devices may be used at the bottom of the belt if desired but they are not necessary it only being necessary to use one direction changing device in this position as shown in Fig. 2. Some means is provided for stopping the belts in the event the press should stop suddenly so that they will act as brakes on the roll of paper and prevent the paper from running off. In Fig. 3 I have shown one construction for this purpose. In this construction the shaft 14a which drives the direction changing device 14 and the belts is connected with a driving shaft 41 by means of a clutch and means are provided for disconnecting the shaft 14a from the driving shaft 41 when the press suddenly stops or slows down, and for applying a brake to the shaft 14a.

In the particular construction illustrated, the shaft 41 is connected with the shaft 14a by a clutch 42 controlled by a sliding member 43 on the shaft 41. This sliding member is actuated by a lever 44 pivoted at 45 and provided with the usual fork which engages the member 43. The lever 44 is actuated by an electro-magnetic device 47 such as a solenoid, the movable part of which is connected with the lever 44 by the member 48. The electro-magnetic device 47 is connected by the conductors 49 and 50 with a circuit controller on the press which completes the circuit therethrough when the press is suddenly stopped or slackened. The lever 44 also actuates a suitable brake for the shaft 14a. The clutch and brake may be of any suitable construction. As herein shown the sliding member 43 is provided with a conical shaped portion 51 which when the device is moved the left of Fig. 4, lifts the ends of the levers 52 so as to actuate the clutch and connect shaft 41 with the shaft 14a. When moved in the opposite direction, the levers 52 are removed to release the clutch. The sliding member 43 is also provided with the conical shaped portion 53 which moves the braking levers 54 pivoted at 55 so as to cause the members 56 thereof to actuate the braking members 57. It will thus be seen that when the press suddenly stops or slows down, the electro-magnetic device 47 will be energized and this will disconnect the shaft 41 from the shaft 14a and apply brakes to the shaft 14a, thus suddenly stopping the belts and the paper being delivered to the press. When the press is again started, the electro-magnetic device is de-energized and the retracting device 58 releases the brake and moves the clutch to connect the shafts 41 and 14a.

The operation of the device is readily seen

from the foregoing. When in operation and the belts are driven, they act to assist in delivering the paper to the press their preferred action being a slight braking action. When one roll is about exhausted the shaft 1 is rotated and the adjacent roll is brought into contact with the expiring web, some adhesive material having previously been placed on the end of the web of the new roll. As the new roll comes into contact with the web from the expiring roll, the new roll is rotated and when the adhesive material comes in contact with the web of the expiring roll, the belts press the web of the expiring roll against the adhesive, thereby causing the web of the new roll to be attached to the web of the old roll and pass into the press so that the supply of the paper is changed from the expiring roll to the new roll. If there is any paper left on the expiring roll when this occurs, the web is then severed so as not to interfere with the paper running from the new roll. It will be seen that due to the arrangement of the belts and their large contact area with the roll, of paper, this construction gives complete and accurate and positive control of the roll of paper from which paper is being supplied to the press, both during the operation of the device and when the press is stopped.

The grooves 29 in the rollers 17 and 18 are preferably of such depth that the belt 12 will be flush with the periphery of the roll. If desired, the belts can be arranged so that they will be driven by the roll of paper instead of by power applied to the shaft 14a, that is, by the pull of the web by the press, this pull being transferred through the roll to the belts. This will give the desired tension to the paper passing to the press. When the belts are not being driven by the shaft 14a, the weights 21 will maintain the necessary tension on the belts to stop the roll of paper by friction in the event the press is suddenly stopped, thereby preventing the paper from being unrolled when this happens. I may use the clutch 42 as a friction device to regulate the tension produced on the paper by the belts in the event the press is suddenly stopped.

It will be noted that each belt is provided with a looped portion, in the particular instance being a portion extending around direction changing devices 14. It will further be seen that as the diameter of the roll of paper varies, the length of this looped portion changes. When the diameter is small, for example, the looped portion becomes longer and when the diameter is large, the looped portion becomes shorter.

In the particular device shown, this looped portion is provided with means for automatically varying its length as the diameter of the roll changes thus keeping the belt in

proper relation to the roll under all conditions.

I claim:

1. A device for delivering paper to printing presses comprising a support for a roll of paper, direction changing devices above and below the roll of paper independently supported, a plurality of endless belts passing about said direction changing devices, means for moving one of the direction changing devices of each belt as the roll from which the paper is being delivered to the press changes in diameter so as to keep said belts taut and in proper contact with said roll, a support for a second roll of paper, and means for moving said support to move said second roll of paper into contact with said belts. 70 75

2. A device for delivering paper to printing presses comprising a support for a roll of paper, a plurality of endless belts adapted to engage said roll of paper, a plurality of direction changing devices over which said belts pass, one of the direction changing devices for each belt being above the roll of paper, another of such direction changing devices of each belt being below the roll of paper, said direction changing devices being independently supported, said belts positioned so that the paper from the roll runs therealong and then passes therefrom to the press, and means for keeping said belts taut as the roll of paper varies in size because of the paper being delivered to the press. 80 85 90 95

3. A device for delivering paper to printing presses comprising a support for a plurality of rolls of paper, a plurality of endless belts adapted to engage one of said rolls of paper, direction changing devices above and below the roll of paper independently supported and about which said belts pass, means for moving the supporting device for the rolls of paper so as to bring the web of the new roll into contact with the web of the expiring roll, the end of the web of the new roll having adhesive thereon so that it is attached to the web of the expiring roll when the belts press the web of the expiring roll against the adhesive end of the web of the new roll and means for automatically adjusting the belt to permit the new roll to be moved to a point where the belt will press the webs of the two rolls together. 100 105 110 115

4. A device for delivering paper to printing presses comprising a support for a plurality of rolls of paper, a plurality of endless belts adapted to engage one of said rolls of paper, direction changing devices above and below the roll of paper independently supported and about which said belts pass, means for moving the supporting device for the rolls of paper so as to bring the web of the new roll into contact with the web of the expiring roll, the end of the web of the new roll having adhesive thereon so that it is attached to the web of the expiring roll when the belts 120 125 130

press the web of the expiring roll against the adhesive end of the web of the new roll and means for keeping said belts taut as the size of the roll varies because of the delivery of 5 the paper therefrom to the press and means for automatically adjusting the belt to permit the new roll to be moved to a point where the belt will press the webs of the two rolls together.

10 5. A device for delivering paper to printing presses comprising a support for a roll of paper, direction changing devices above and below the roll of paper independently supported, a plurality of endless movable

15 belts passing about said direction changing devices, means for moving one of the direction changing devices of each belt as the roll from which the paper is being delivered to the press changes in diameter so as to keep 20 said belts taut and in proper contact with said roll, and means for suddenly stopping the movement of the belts when the press is suddenly stopped.

6. A device for delivering paper to printing presses comprising a support for a roll of paper, a plurality of endless belts, direction changing devices at opposite ends of each belt, one of said direction changing devices being movable with relation to the other, 25 means for moving the movable direction changing device of each belt as the roll becomes smaller by the removal of the paper therefrom, the paper engaging the belt and passing over the same direction changing device as the belt at one end thereof.

7. A device for delivering paper to printing presses, comprising a support for a roll of paper, a plurality of endless belts, direction changing devices at opposite ends of 40 each belt, one of said direction changing devices being movable with relation to the other, means for moving the movable direction changing device of each belt as the roll becomes smaller by the removal of the paper therefrom, the paper engaging the belt and 45 passing over the same direction changing device as the belt at one end thereof, the direction changing device being recessed for the belt at this point.

50 8. A device for delivering paper to printing presses comprising a support for a plurality of rolls of paper, a plurality of endless belts adapted to engage one of said rolls of paper, direction changing devices above and 55 below the rolls of paper which support the belts, when in contact with one of said rolls of paper, in a curved position in a vertical plane with the concave side of the curve opening laterally toward said rolls, the upper 60 and lower direction changing devices being in a vertical plane which passes through the roll of paper, thereby giving a large contact area of the belts with the paper, the belts being provided with tensioning devices which 65 keep them in contact with the paper as the

roll is reduced in diameter by delivering the paper into the press, and means for moving the supporting device for the rolls of paper so as to bring the web of the new roll into contact with the web of the expiring roll, the 70 space between the top and bottom direction changing devices of the belt being sufficient to permit the new roll to enter into the space between them to engage said web, the belts pressing the web of the expiring roll against 75 the adhesive end of the web of the new roll to connect the two webs together and change the feed to the new roll while the press is running at a high speed.

9. A device for delivering paper to printing presses comprising a support for a plurality of rolls of paper, a plurality of endless belts adapted to engage one of said rolls of paper, direction changing devices above and below the rolls of paper which support the 85 belts, when in contact with one of said rolls of paper, in a curved position in a vertical plane with the concave side of the curve opening laterally toward said rolls, the upper and lower direction changing devices being in 90 a vertical plane which passes through the roll of paper, thereby giving a large contact area of the belts with the paper, the belts being provided with tensioning devices which keep them in contact with the paper as the roll is 95 reduced in diameter by delivering the paper into the press, and means for moving the supporting device for the rolls of paper so as to bring the web of the new roll into contact with the web of the expiring roll, the space 100 between the top and bottom direction changing devices of the belt being sufficient to permit the new roll to enter into the space between them to engage said web, the belts pressing the web of the expiring roll against 105 the adhesive end of the web of the new roll to connect the two webs together and change the feed to the new roll while the press is running at a high speed, one only of the direction changing devices for each belt being 110 driven.

10. A delivery device for delivering paper to printing presses comprising a support for a roll of paper, a plurality of endless belts in contact with said roll of paper for governing the rotation thereof, direction changing devices above and below the roll of paper when in position, over which said belts pass, said direction changing devices being on a vertical line which passes through the roll of paper, a driving device for said belts for causing them to move about said direction changing devices, means for keeping said belts in contact with the roll of paper as it decreases in diameter, and means for suddenly stopping the movement of said belts when the press is suddenly stopped.

11. A delivery device for delivering paper to printing presses comprising a support for a plurality of rolls of paper, a plurality of 120

belts adapted to engage one of said rolls of paper, direction changing devices above and below the roll of paper over which said belts pass, said direction changing devices being in a line which passes through the roll of paper when in its operative position, and means for moving the supporting device for the rolls of paper so as to bring the web of a new roll into contact with the web of the 10 expiring roll, the end of the web of the new roll having adhesive thereon so that it is attached to the web of the expiring roll when the belts press the web of the expiring roll against the adhesive end of the web of the 15 new roll.

12. In combination in paper web control means, a magazine stand for the paper reels, means for rotating the stand to bring the reels successively into web delivery position, 20 an endless belt making frictional contact with the periphery of the reel in web delivery position, two pulleys over which the belt passes, one of the pulleys being anchored above the said reel and another being anchored lower than the said reel such that the 25 periphery of this reel deflects the endless belt between the pulleys, and means for taking up belt slack as the reel periphery decreases due to the reel exhausting.

13. In combination in paper web control means, a magazine stand for the paper reels, means for rotating the stand to bring the reels successively into web delivery position, an endless belt making frictional contact 30 with the periphery of the reel in web delivery position, two pulleys over which the belt passes, one of the pulleys being anchored above the said reel and another being anchored lower than the said reel such that the 35 periphery of this reel deflects the endless belt between the pulleys, and a third pulley movably mounted with the belt passing round it so as to take up belt slack as the reel periphery decreases due to the reel exhaust- 40 ing.

14. In combination in paper web control means, a magazine stand for the paper reels, means for rotating the stand to bring the reels successively into web delivery position, 45 an endless belt making frictional contact with the periphery of the reel in web delivery position, two pulleys over which the belt passes, one of the pulleys being anchored above the said reel and another being anchored lower than the said reel such that the 50 periphery of this reel deflects the endless belt between the pulleys, and automatic compensating means acting as a guide for the belt and to take up slackness of the belt as 55 the reel diameter decreases.

Signed at Chicago county of Cook and State of Illinois, this 21st day of April 1928.

DAVID G. BERNARD.
